CLAIM

The ornamental design for a laryngoscope assembly, as shown and described.

DESCRIPTION

FIG. 1 is a first perspective view of the laryngoscope assembly;

FIG. 2 is a right side elevational view of the laryngoscope assembly;

FIG. 3 is a left side elevational view of the laryngoscope assembly;

FIG. 4 is a back elevational view of the laryngoscope assembly;

FIG. 5 is a front elevational view of the laryngoscope assembly;

FIG. 6 is a top plan view of the laryngoscope assembly;

FIG. 7 is a bottom plan view of the laryngoscope assembly;

FIG. 8 is a second perspective view of the laryngoscope assembly; and,

FIG. 9 is a cross-section view of the laryngoscope assembly taken in the direction of line 9-9 of FIG. 4.

1 Claim, 7 Drawing Sheets
